UNITED STATES PATENT OFFICE.

JEAN G. DUPONT, OF CHICAGO, ILLINOIS.

DESIGN FOR A NURSING-BOTTLE COVER.

Application filed January 26, 1925. Serial No. 12,142. Term of patent 7 years.

To all whom it may concern:

Be it known that I, JEAN G. DUPONT, a citizen of the United States, residing at Chicago, in the county of Cook and State of Illinois, have invented a new, original, and ornamental Design for a Nursing-Bottle Cover, of which the following is a specification, reference being had to the accompanying drawing, forming a part thereof.

In the drawing:

Fig. 1 is a front elevation of a nursing bottle cover embodying my new design. Fig. 2 is a section on line 2—2 of Fig. 1.

I claim:

The ornamental design for a nursing bottle cover, as shown.

Chicago, Ill., Jan. 22, 1925.

JEAN G. DUPONT.
